PRINTING DEVICE

Filed July 23, 1928

UNITED STATES PATENT OFFICE

ELMER F. RICHTER, OF PARK RIDGE, ILLINOIS, ASSIGNOR TO ADDRESSOGRAPH COMPANY, OF CHICAGO, ILLINOIS, A CORPORATION OF DELAWARE

PRINTING DEVICE

Application filed July 23, 1928. Serial No. 294,754.

This invention relates to printing devices of the kind which are adapted to be run through an addressing machine for taking impressions therefrom and to be stored in trays or drawers in accordance with any desired classification.

The object of this invention is to provide a printing device which is light in weight but which has a relatively large information space and is provided with retaining means for detachably holding a printing plate having embossed type characters thereon.

And a further object of the invention is to provide a cardboard printing device having an opening in which a printing plate is detachably mounted in a strong and substantial manner.

In the accompanying drawings I have shown selected embodiments of the invention and referring thereto

Fig. 1 is an elevation of a printing device with one kind of retaining means for detachably holding the plate.

Fig. 2 is a sectional view on the line 2—2 of Fig. 1.

Fig. 3 is an enlarged sectional view on the line 3—3 of Fig. 1.

Fig. 4 is an elevation of a printing device having another form of plate retaining means.

Fig. 5 is a sectional view on the line 5—5 of Fig. 4.

Fig. 6 is a sectional view on the line 6—6 of Fig. 4.

Fig. 7 is a detail view showing the lower portion of printing plate 18.

Referring to Figs. 1—3 of the drawings, the printing device comprises a body 7 which may be made of cardboard or other light material having an opening 8 in its lower portion to receive a printing plate 9 having type characters embossed thereon for printing an address or other matter. A backing 10 is arranged on the back of the body over the opening 8 and it is provided with prongs 11 which are forced through the body for securing the backing to the body. At the lower edge of the backing the central portion 10' thereof extends below the lower edge of the opening 8 and prongs 11' are provided on this

extension to engage the body like the prongs 11. On each side of this extension 10' the lower edge of the backing is bent to form beads 12, 12 to receive the lower edge of the plate 9. Lips 13 are stamped up from the backing to engage the ends of the plate 9 and co-operate with the beads 12 for holding the plate on the backing. In this form of my invention the plate is provided with notches 14, and yielding locking devices 15 are formed from the backing to engage these notches for locking the plate in place on the backing. The end edges of the opening 8 are cut away at 16 to permit access to the locking devices 15 for depressing them to permit removal of the plate. In the construction of Figs. 4—6 the backing is provided with a yielding locking device 17 to engage one end of the plate 18 and with a lip 19 to engage the other end of the plate, and the bottom edge of the backing is bent to form a bead 20 which has a plurality of parallel inclined spaced slits or cuts 21 with the upper corners 22 formed by said cuts inturned to engage or to lie in close proximity to the body of the backing. The printing plate 18 is provided at its lower edge with inclined teeth or projections 23 which are adapted to engage the slotted bead 20 by a downward movement, and to interlockingly engage the inturned corners 22 by a lateral movement from right to left, Fig. 4. The opening 8' in the body is somewhat larger than the plate so that the latter may be placed upon the backing over the locking device 17 and then moved down until the teeth or projections 23 engage the bead after which the plate is moved laterally to the left, Fig. 4, to engage the lip 19 whereupon the locking device 17 will engage the other end of the plate. This plate is held on the backing against endwise movement by the lip 19 and the locking device 17, against up movement by the teeth or projections 23 and the inturned corners 22, and against down movement by the bead 20, so that it will be held in proper position on the backing and in the opening of the body just as the plate 9 is held in the body of Fig. 1. The openings 8 and 8' are made as wide as desired to accommodate particular printing plates or

printing plates of different widths, including the widest plates. In the construction of Fig. 1 all of these plates will be provided at the same location with notches 14 to engage the locking devices 15; in the construction of Fig. 4 all of the printing plates will be provided with the teeth or projections 23. The body can be made in any desired size and it is capable of being made large because it is not only light in weight but because substantial provision is made for mounting therein the detachable printing plate. The backing may be made of metal, in which case the prongs can be stamped up therefrom, or the backing can be made of other material and prongs or staples or other well-known and suitable fastening devices provided for securing the backing to the body. Both faces of the body may be ruled or printed in any manner for receiving record information and classifying or selecting means may be located in or on the margins of the body in a well known manner. The backing constitutes a strong and substantial support for the printing plate and from which the retaining means may be formed by stamping. Printing plates of various widths may be used interchangeably in the device and in Fig. 1 I have indicated a narrow size plate and in Fig. 4 a wide size plate. The plate of Fig. 1 may be inserted in the lips 13 at its lower corners and then moved down on the backing over the locking devices 15 until the latter engage the notches, and this plate may be removed by depressing both locking devices and then sliding the plate up until it clears the lips. Or the plate of Fig. 1 may be inserted by arranging it in an inclined position engaging the left lip 13 and the left end notch engaging the left locking device, as indicated in broken lines in Fig. 1, and then moving it down into engagement with the right lip 13 and until the right notch engages the right locking device. To facilitate insertion and removal of the plate 9 it may be cut away at 24 at its right end and lower corner, Fig. 1. The plate 18 in Fig. 4 is inserted, as before explained, by arranging it on the backing over the locking device 17 and then moving it down into the bead 20 and laterally to the left under lip 19 until locking device 17 engages its right end; and this plate may be removed by depressing locking device 17 and moving the plate to the right and up on the backing out of bead 20.

I am aware that changes in the form, construction and arrangement of parts may be made without departing from the spirit or sacrificing the advantages of the invention and I reserve the right to make all such changes as fall within the scope of the following claims.

I claim:

1. A printing device comprising a body having an opening therein, a printing plate having printing characters thereon, means

on the body for supporting said printing plate in said opening, and retaining means on said supporting means for securing the printing plate thereon.

2. A printing device comprising a body 70 having an opening therein, a printing plate having printing characters thereon, a backing on said body over said opening, and means on said backing for retaining the printing plate thereon and in said opening. 75

3. A printing device comprising a relatively large body made of light material and having an opening therein to receive a printing plate, a backing of substantial material secured to the body over said opening, a 80 printing plate having printing characters thereon, and retaining means on the backing for detachably securing the printing plate thereon and in said opening.

4. A printing device comprising a card-board body having an opening therein to receive a printing plate, a metal backing secured on the back of the body over said opening, a printing plate having printing characters thereon, and retaining means on the 90 backing for detachably securing the printing plate on the front of the backing and in said opening.

5. A printing device comprising a body having an opening therein, a metal backing secured to the body over said opening, a printing plate having printing characters thereon, and retaining means struck up from the backing for engaging the printing plate at its margin for detachably securing the 100 printing plate on the backing and in said opening.

6. A printing device comprising a body having an opening therein to receive a printing plate, a metal backing secured to the 105 body over said opening, a printing plate having printing characters thereon, said opening being of sufficient width to receive relatively large printing plates, and retaining means integral with the backing and located 110 adjacent edges of the opening for engaging edges of the printing plate to detachably secure a printing plate on the backing and in said opening.
